ELECTRICAL CONNECTER PLUG

Lee Hunter Riley, University City, Mo.

Application March 20, 1936, Serial No. 69,811

1 Claim. (Cl. 173—328)

My invention relates to electrical connectors for general use, including use in outlet boxes and as a connection between lamps and other electrical devices and their source of electric current.

The invention has as its principal object a connector that is simple, sturdy and inexpensive, that is neat and inconspicuous in appearance, whose socket member is adapted for concealment by means of a false cover plug that minimizes the danger of electrical shocks, that minimizes the risk of fraying or breaking the electric wiring and that has other important practical advantages.

The invention consists in the electrical connector plug and in the parts and combinations and arrangements of parts hereinafter described and claimed.

In the accompanying drawings,

Fig. 1 is a part elevation, part vertical sectional view, on a reduced scale, of an electrical lamp having mounted in its base an electrical connector plug embodying my invention and also showing one of said plugs used as a wall outlet member,

Fig. 2 is a part elevation, part vertical sectional view of the base portion of said lamp,

Fig. 3 is a vertical sectional view of an outlet box having mounted therein a connector plug embodying my invention,

Fig. 4 is an elevation of the socket member of said device, looking in the direction of the arrows 4—4,

Fig. 5 is an elevation of the plug member looking in the direction of the arrows 5—5,

Fig. 6 is a longitudinal sectional view through the two parts of the connector plug device shown in Fig. 3,

Fig. 7 is a sectional view similar to Fig. 6, but showing the two parts of the device separated and ready for assembly,

Fig. 8 is a sectional view on the line 8—8 of Fig. 6,

Fig. 9 is a sectional view on the line 9—9 in Fig. 6,

Fig. 10 is a sectional view on the line 10—10 of Fig. 5,

Fig. 11 is a detail view similar to Fig. 3 showing the socket member in place and having a closure plug mounted in the end thereof,

Fig. 12 is a perspective view of said plug, and

Fig. 13 is a sectional view of a modified binding post and wire terminal construction.

Fig. 1 shows electrical connector plug devices embodying my invention indicated generally by the numeral 1. One of said devices is mounted

in an outlet box 2 at the base board level of a wall 3 and one in the base 4 of the tubular standard 5 of an electric lamp 6. The connector plug device 1 comprises a socket member 7 and a plug member 8.

The socket member 7 is held in place in the base 4 of the lamp standard 5 by means of a set screw 9. The lamp wiring 10 extends from said socket member 7 through the lamp standard 5 to the light bulb socket. The plug member 8 that cooperates therewith is mounted at the end of a suitable extension cord 11.

Fig. 3 illustrates an outlet box 2 mounted in a wall 3 at the base board level. Said outlet box 2 has a perforated cover 12 secured thereto as by screws 13 and a tubular housing 14 is mounted in the opening thereof and secured thereto, as by welding 15, said housing 14 projecting inwardly into the outlet box 2 and outwardly into an opening 16 in the base board 17, terminating flush with the outer surface of said base board. The housing 14 has an annular rib 18 formed in its interior near the inner end thereof, which serves as a stop for the beveled inner edge 19 of the socket member 7. The plug member 8 is secured to the end of the extension cord 11 to whose other end is secured the plug member 7 that cooperates with the socket member 8 in the lamp.

The two wires 20 of the electric wiring system extend into the socket member through holes 21 in the end wall 22 thereof, and the insulation 23 is stripped from the end portions thereof, said holes being provided with a reduced portion 24 too small in size to receive the wire 20 when covered by insulation 23, the end of the insulation resting against one face of the shoulder 25 formed by said reduced portion 24. Against the other face of each shoulder 25 is mounted the end portion 26 of a contact strip 27, said end portions having recesses 28 therein receiving the ends of said wires 20. Screws 29 mounted in countersunk openings 30 in the sides of the socket member 7 are threaded through the end portions 26 of the contact strips 27 to engage the ends of the wires 20 and hold them in place.

The plug member 8 has recesses 31 in the end that fits in the socket, said recesses 31 being in line with the contact strips 27, but of larger size. Mounted on either side of a cross wall 32 separating said recesses 31 and projecting into said recesses are contact members 33 into which extend the plain ends of the two wires 34 of the extension cord 11 from which the outer cover 35 and the in-

dividual insulation 36 have been removed. These wires 34 are held in place in their respective contact members 3 by means of screws 37 set in countersunk openings 38 in the plug and extending through the plug and far enough through the contact members to engage the wires 34. The bores 39 through which the stripped wires 34 extend are of reduced diameter intermediate their ends to form a shoulder 40 against one side of 5 which one of said contact members 33 abuts and the other side of which prevents the insulation 36 from extending into the contact member. The two wire bores 39 open into a single large bore 41 at the end of the plug, which large bore 10 41 is closed by an annular cap 42 fitting over the extension cord 11.

The socket member 7 is provided at its outer end with a bayonet slot comprising a longitudinally extending portion 43 and an angularly offset portion 44. The socket member 7 extends slightly beyond the face of the base board 17 and the plug member 8 has an annular peripheral rib 45 that overlaps the end of the socket member. Mounted in the annular channel 46 formed between said rib and the plug body are springs 47 15 which preferably have one end 48 embedded in the plug material.

As appears from Fig. 7, the plug 8 is arranged in line with the socket 7 and then moved endwise 20 into the socket, the contact strips 27 entering the enlarged recesses 31 in which the contact members 33 of the plug are mounted. The plug has a pin 49 that moves along the longitudinal slot 43 in the socket until it seats against the angular portion 44 of the slot, whereupon twisting movement of the plug to move the pin into the angular locking portion 44 of the slot swings the plug into such position that the contact members 33 thereof are in engagement with the contact strips 27 25 of the socket member. Preferably, both sets of contact members have curved bosses 50 which accommodate the locking movement of the plug and which insure firm electrical contact. The springs 47 in the end of the plug maintain the parts in 30 locked position and prevent accidental disengagement.

It will be understood that the foregoing detailed description of the plug and socket members mounted in the outlet box and of the wiring 35 connections thereof is also applicable to the plug and socket members in the lamp.

As appears from Figs. 11 and 12, wall sockets which are not in use may be closed by a plug 51 40 conforming in finish to the base board and having a locking pin 49 therein. The use of such a plug prevents trapping of dirt and makes the 45 socket quite inconspicuous.

In Fig. 13 is shown a slight modification where- 5 in the end portion 60 of the wire is permanently mounted in a contact adapter 61 which extends into the bore of the end portion 26 or 63 of the contacts 27 or 33. Preferably, the adapter has a rib 62 at its end which is engaged by contact screws 29 or 37 to prevent separation of the parts.

The plug and socket members may be made of a suitable plastic, as a resin, or any other suitable composition and the contact members and the springs may be molded or cast therein.

The above described construction removes all strain from the electric wiring and separation of the two parts of the connector can be effected only by pressure on the plug against the force of the springs and twisting of the plug to release the bayonet lock. Thus, accidental disengagements of the parts and breaking or shorting of the electrical circuit are prevented. The electrical contact is positive and certain. The changing of 20 cords is facilitated and a cord of the length desired at any one place may be used instead of the lamp or other device having a cord of excess length projecting therefrom. Breakage and fraying 25 of the electric cord are prevented. The connector is simple and inexpensive in construction, it is sturdy and durable, it is neat and inconspicuous in appearance and it is adapted for use wherever an electrical connector is needed. For example, it may be used in a ceiling for the separable mounting of light sockets or other fixtures.

Obviously, numerous changes may be made without departing from the invention and I do not wish to be limited to the precise construction shown.

What I claim is:

An electrical connector plug comprising a tubular socket member having an end wall, resilient electrical contact members projecting from said end wall into the socket of said member, and a plug member fitting in said socket, said plug member having recesses in its end and electrical contact members in said recesses for external engagement with the respective contact members of the socket members, said contact members all having curved contact bosses, said socket member having a longitudinal slot at its outer end and an angular slot communicating with said longitudinal slot and said plug having a pin for cooperation with said slots and having an annular peripheral rib forming a channel between itself and the body of the plug and springs in said channel bearing against the end of the socket member for resisting separation of the parts.
